LADY'S HANDBAG

Edward Q. Farnsworth, Los Angeles, Calif., assignor to Angelus Souvenir & Mfg. Co., Los Angeles, Calif.

Application February 23, 1955, Serial No. 34,639

Term of patent 14 years

(Cl. D87—3)

I claim:

The ornamental design for a lady's handbag, as shown.
